UNITED STATES PATENT OFFICE.

CHARLES E. RICE, LEWIS B. McDONALD, AND JAMES D. McDOWELL, OF
LITTLE ROCK, ARKANSAS.

WEIGHT-MOTOR.

SPECIFICATION forming part of Letters Patent No. 494,693, dated April 4, 1893.

Application filed May 25, 1892. Serial No. 434,332. (No model.)

To all whom it may concern:

Be it known that we, CHARLES E. RICE, LEWIS B. McDONALD, and JAMES D. McDOWELL, of Little Rock, Arkansas, have jointly made a new and useful Improvement in Weight-Motor, of which the following is a full, clear, and exact description.

The novelty in the present invention consists in the means and mechanism and in the construction and combination of the parts as set forth and claimed.

The most desirable mode of carrying out the improvement is exhibited in the annexed drawings, making part of this specification, in which—

Figure 1 is a side elevation (a portion of the frame-work broken away) of the improved apparatus; Fig. 2 a vertical section on the line 2—2 of Fig. 1; Fig. 3 a vertical section upon the line 3—3 of Fig. 2; Fig. 4 a plan of the parts shown in Fig. 3; Fig. 5 a plan of the portion (the right hand portion as shown in Fig. 1) of the apparatus containing the capstan; Fig. 6 a side elevation of the eccentric gearing, the parts being as when the pump-rod is moved downward; Fig. 7 a similar view of the eccentric gearing, the parts being as on the up-stroke of the pump-rod; and Fig. 8 a plan of the parts of Fig. 6. The last six named views are upon an enlarged scale.

The same letters of reference denote the same parts.

The frame-work of the apparatus is usually, and mainly, in the form of a tower, A, substantially as shown. The weight, B, which may be of any preferred form and nature, is attached to a rope or other suitable tie, C, which is carried over an overhead or upper bearing, such as the sheave D, arranged at a suitable elevation in the tower, and thence to a part such as the drum, E, upon which the rope is adapted to be wound. The drum is attached to a shaft, e, journaled at e', e', and it also carries, or is extended to form, another drum, E', preferably of larger diameter than that of the drum E, upon which another rope F, is adapted to be wound. The last named rope leads from the drum, E', to a capstan G. To suit the relative arrangement of said drum and capstan an intermediate bearing, H, for

the rope is employed as shown. The capstan can be operated by any suitable power, such for instance as a horse-power, applied to the capstan bar g, and when the capstan is rotated the rope, F, is unwound from the drum E', and wound upon the capstan, and the other rope C, is thereby wound upon its drum E, and the weight elevated to the desired level.

We desire not to be restricted to the means described, or any particular means, for raising the weight: neither to any special arrangement or construction of drum or other part upon which the weight-rope is wound, and whereby the power of the weight is stored to be used at will. We, however, prefer the means exhibited.

Under some circumstances the described weight-power can be taken off from the pulley, drum, shaft, or other part upon which the rope is wound, quite directly, but, to more fully carry out the improvement, and to multiply the motion of the shaft e, the following arrangement is preferably adopted. Said shaft, e, is provided with a gear, I; this gear engages with a pinion J attached to a shaft j, that is journaled in bearings j', j', and provided with a gear J'; said last named gear in turn engages with a pinion K, upon a shaft, k, that is journaled in bearings k', k', all substantially as shown. The shaft k, is thus driven from the shaft, e, and at a much higher rate than that of the shaft e. Its rate, however, is substantially uniform as long as the weight is descending, but its motion, in turn, is communicated to produce a variable rotary motion in another shaft l, journaled at l', l', and, preferably as follows: two gear wheels K' and L, are hung eccentrically upon their respective shafts k and l, and engage with each other substantially as shown; the shaft l is thus driven by the shank k, and at every revolution thereof it is driven part way round, say, half way round, more rapidly and the remainder of the revolution less rapidly, and the leverage increased during the slower movement and lessened during the quicker movement. The gear wheels are preferably circular, although gear wheels hung eccentrically and combined as described, but of a different contour, might be used. The shaft, l, in the present instance is, and by means of

85

the crank M, connected directly with the pump-rod, N, of the pump, and it might be termed the pump-rod shaft. The pump itself is not shown. It is of any of the customary forms adapted to be driven by a reciprocating motion.

The relative arrangement of the wheels K', L, is shown more distinctly in Figs. 6 and 7. In Fig. 6 the pump-rod is supposed to be making its down-stroke, and the driven shaft, l, is moving at its maximum rate, and the driving shaft k is exerting its least power. But as the pump is supposed to be a single acting one it is only necessary to lower the pump-rod and 15 pump-plunger, and for this work but little, if any, power is needed, and the sooner the pump-plunger or bucket is brought into position to act the better. In Fig. 7, the pump-rod is supposed to be on its up-stroke, and 20 the driven shaft is moving at its slowest rate, and the driving shaft is exerting its maximum power, which is desirable in view of the fact that the load is now being lifted. Thus, at each revolution of the driving shaft, 25 its power increases with the work to be performed, and diminishes as the load is lightened. An important feature, however, of this portion of the mechanism is the means for regulating the described motion of the eccentric gearing.

O represents what might be termed a counterbalance, preferably in the form of a weighted arm fastened to the shaft l, and projecting therefrom in the opposite direction to that of 35 the crank M: it serves to balance the pump-rod both in its upward and in its downward movement, at least to an extent sufficient to prevent the rate of the motion of the parts from changing too abruptly. The weight o is 40 adjustable upon the arm O toward and from the shaft l.

An additional feature is a governor P, shown more fully in Figs. 3 and 4. In its most desirable form it consists mainly of an 45 arm p, secured to the shaft k to rotate therewith. At one of its ends, and preferably at its ends respectively, it is provided with vanes p' and p² which are adapted as the rotation of the shaft k is accelerated, to open or turn 50 more flatwise and thus offer more resistance to the rotation of the shaft, and, on the other hand, when the shaft motion is slackened, to turn more edgewise and offer less resistance. To this end the vanes are each jointed at the 55 inner end, p³, thereof to the arm p to enable the vanes to turn thereon as indicated by the positions of the vanes shown in the full and in the broken lines in Fig. 3, and, at a point between the inner and outer end of 60 the vane, are elastically connected with the arm by means of the spring p⁴, substantially as shown. That is, the spring yields when the shaft motion is accelerated, allowing the vane to open, and, when the shaft motion is 65 checked, the spring acts to turn the vane into its full-line position. The arm, p, may be weighted, as at p⁵, p⁶.

To enable the weight to be wound up without working the pump-rod and the parts more immediately therewith connected, the shaft 70 j and gear J' are adapted to be connected by means of a pawl-and-ratchet mechanism Q which acts to unite the gear and shaft to turn together only when the weight is running down.

In operation, the weight, in the manner indicated, is elevated to the preferred height and there upheld until it is desired to operate the pump. Whatever has been applied to the capstan for rotating it in effecting the 80 elevation of the weight is suitably disconnected therefrom to leave the capstan and drums free to turn whenever the weight is allowed to drop. Any suitable means, (not shown) may be employed to secure the weight 85 in its up-position, and to free it when it is to be dropped, and for braking the weight in its descent. On releasing the weight its rope acts to effect the rotation of the drums and the various shafts and gears in the direction 90 indicated by the arrows x, Fig. 1, and the pump-rod and pump are accordingly operated. After its power is exhausted the weight is again elevated, and the operation is repeated.

We desire not to be restricted to a pump 95 in the use of the herein-described mechanism. That is, the rod M might be any reciprocating part. Nor do we wish to be limited to the eccentric gearing for transmitting the drum-shaft motion, derived from the falling 100 weight, to the pump-rod.

We claim—

1. In a pumping mechanism, in combination with a primary train of gearing, an eccentric gear engaging the last wheel of the 105 train, another eccentric gear engaging that first mentioned, a crank on the shaft of the last-referred-to eccentric gear, and a counterbalance between the crank and said last gear.

2. In a pumping mechanism, in combination with a primary train of gearing, an eccentric gear engaging the last gear of the train, another eccentric gear engaging that first mentioned, stationary bearings for the 110 shafts of said eccentric gears, a crank on the shaft of the last-referred-to eccentric gear, an adjustable counterbalance between the crank and said last gear, said eccentric gears being so arranged as to allow a rapid downward movement and to cause a slow and powerful upward movement, substantially as set forth.

3. The governor consisting of the weighted arm, and the eccentrically-held pivoted vanes, 115 substantially as described.

Witness our hands this 20th day of May, 1892.
